ROBERT C. COLE, OF HARTFORD, CONNECTICUT, ASSIGNOR TO THE JOHNS-PRATT COMPANY, OF HARTFORD, CONNECTICUT, A CORPORATION OF CONNECTICUT.

FUSIBLE ELEMENT FOR ELECTRIC CUT-OUTS.

1,188,152.

Specification of Letters Patent. Patented June 20, 1916.

Application filed July 30, 1915. Serial No. 42,854.

To all whom it may concern:

Be it known that I, ROBERT C. COLE, a citizen of the United States, residing at Hartford, in the county of Hartford and State of Connecticut, have invented a new and useful Improvement in Fusible Elements for Electric Cut-Outs, of which the following is a specification.

This invention relates to the construction of fusible links for inclosed fuses. It is desirable to have a fuse link disrupt and open the circuit at an exact predetermined time under overload conditions. This is particularly desirable on what is known as maximum load circuits, that is, circuits on which a customer is permitted to use any desired amount of current up to a certain quantity, but no more. On such circuits the load usually increases very gradually, and where there is a gradual increase in overload a fuse link is liable to soften and perhaps melt and yet "hang," that is, remain in a softened or liquid state and still be a conductor capable of carrying current, although the maximum has been exceeded.

The object of this invention is to provide mechanically operating means which will insure the rupture of the link and the opening of the circuit when the fusible metal becomes melted or softened, and thus eliminate the possibility of the flow of a greater current than is intended, no matter how gradually the overload increases. To attain this end a spring is connected with the fusible element in such manner that when the metal softens the spring owing to its resilience instantly causes the link to be ruptured.

Figure 1 of the accompanying drawings shows a plan of a fuse link constructed according to this invention. Fig. 2 shows a side view of the same. Fig. 3 shows a link of modified form. Fig. 4 shows a side view of the modified form. Fig. 5 shows another modification. Fig. 6 shows a side view of the form shown in Fig. 5. Fig. 7 shows still another modification, and Fig. 8 shows a cross section of the modification shown in Fig. 7.

These links may be used in any of the common types of inclosed and filled fuses with the usual casings and terminal con-

tacts. The link 1 may be made of any suitable fusible metal, desirably zinc; it can have any desired cross sectional shape, and it usually is provided with copper terminals 55 2 of sufficient size to carry the required current. The links may be calibrated by a perforation 3, as shown in Fig. 1; or by notches 4, as shown in Fig. 3; or they may be plain, that is, without any calibration 60 cuts, as shown in Fig. 5. Attached to the links are springs 5. These springs may be made of steel, phosphor-bronze, or any suitable metal which will not lose its temper under such heat as is liable to be generated 65 in the fuse. The springs may be fastened to the links by rivets, as shown in Fig. 1; or they may be clipped to the links by parts 6 that are folded around the edges, as shown in Fig. 3.

Connected with the free end of the spring 70 may be a stud 7 that passes through the link and has a head 8 on the other side which extends beneath the link in such manner that when the metal is softened by excess 75 current the pull of the spring on the stud will cause the head to rupture the link. Instead of a stud a loop 9 may be used, as shown in Fig. 3, which loop is pulled by the spring so that when the metal is softened 80 the link is ruptured. Instead of a pulling spring, such as is shown in Figs. 1 and 3; a pressing spring, of the character shown in Fig. 5, may be used, in which case the stud 10 may have a head 11 bearing down 85 upon the link in such manner that when the metal is softened the spring will cause it to break apart. If desired, as shown in Figs. 7 and 8, an expansion spring 12 may 90 be thrust under compression into the calibration perforation of a link in such manner that when the metal softens the arms of the spring will throw out and rupture the link.

A fusible element constructed in this manner may be calibrated for overload with great accuracy, and will open a circuit more exactly with a smaller overload than when the link is merely calibrated and the entire rupturing action depends upon the physical 95 change resulting from the heating action of the current.

The invention claimed is:

A fusible element for inclosed electric cut-outs consisting of a link of metal adapted to be fused when the current reaches a predetermined maximum, and a metallic spring mounted upon and fastened to the fusible link adjacent to the section which will be fused and arranged to exert tension

transversely upon the section that will fuse when the current reaches the predetermined maximum.
